(57) **CLAIM**

The ornamental design for a coupled artificial teeth, as shown and described.

DESCRIPTION

1. Coupled artificial teeth

1.1 : Front

1.2 : Back

1.3 : Right

1.4 : Left

1.5 : Top

1.6 : Bottom

1.7 : Perspective

1.8 : Perspective

1.9 : Cross sectional

1.10 : Cross sectional

1.11 : End face view as taken along line A-A

1.12 : End face view as taken along line B-B

1.13 : End face view as taken along line C-C

1.14 : End face view as taken along line D-D

1.15 : End face view as taken along line E-E

1.16 : End face view as taken along line F-F

This article is a set of maxillary coupled artificial teeth and mandibular coupled artificial teeth; the maxillary coupled artificial teeth comprises 14 artificial teeth which include 2 artificial teeth for maxillary middle incisor, 2 artificial teeth for maxillary lateral incisor, 2 artificial teeth for maxillary dog teeth, 2 artificial teeth for maxillary 2 first premolar, 2 artificial teeth for maxillary second premolar, 2 artificial teeth for maxillary first molar and 2 artificial teeth for maxillary second molar; the mandibular coupled artificial teeth comprises 14 artificial teeth which are 2 artificial teeth for mandibular middle incisor, 2 artificial teeth for mandibular lateral incisor, 2 artificial teeth for mandibular dog teeth, 2 artificial teeth for mandibular 2 first premolar, 2 artificial teeth for mandibular second premolar, 2 artificial teeth for mandibular first molar and 2 artificial teeth for mandibular second molar.
